UNITED STATES PATENT OFFICE.

WARREN K. LEWIS, OF NEWTON, MASSACHUSETTS, ASSIGNOR TO HUMBLE OIL & REFINING COMPANY, OF HOUSTON, TEXAS, A CORPORATION OF TEXAS.

APPARATUS FOR DISTILLING DECOMPOSABLE MATERIALS.

Application filed November 10, 1922. Serial No. 599,983.

The present invention relates to the art of distillation and will be fully understood from the following description taken in connection with the accompanying drawing, in which Fig. 1 represents in vertical section one form of apparatus contemplated in the invention, and Figs. 2, 3, and 4 are similar views of modifications.

In the distillation of many materials, there is a comparatively large amount of refluxing into the still, even when the vapor line from the still to the condenser is covered with heat-insulation of the best attainable types. With such refluxing there results not only a loss in efficiency to the extent that the initial work of vaporization is undone and must be repeated, but there is an increased decomposition of material needlessly returned and subjected to heating. And where lubricating oils for example, are the material being distilled, such decomposition or cracking lowers the viscosity and flash point.

In proceeding in accordance with the present invention, generally speaking I provide a path for the vapors which is guarded against substantial temperature drop up to the zone where it is intended that condensations occur. One form of apparatus that may be advantageously used, particularly where application of a vacuum is also desired, is shown in Fig. 1, the vaporizing receptacle here being a vertical cylindrical shell 1 mounted over a suitable heater chamber 2. A vapor passage 1' preferably of substantially unrestricted cross section, in accordance with the co-pending application of Warren K. Lewis and Nathaniel E. Loomis, Ser. No. 609872 extends about the receptacle to a condenser zone in the latter containing a cooling coil 9 with inlet and outlet for the circulating fluid, a drip deflector 10 and a collecting pan 11 connecting with a pipe leading to a suitable receiver (not shown, for simplification). From the condenser a pipe 12 leads, if necessary, through an auxiliary condenser 13, to a vacuum-pump and gas-holder according as may be required by the material being distilled. The auxiliary condenser 13 has connections 14, 15 for cooling liquid, and the pipe 16 has a drain 17 below leading to any suitable tank.

A perforated pipe 4 in the bottom of the vaporizing receptacle provides an inlet for

steam or a gas when such may be desired in connection with the distillation; and suitable feed and discharge pipes for the still may be arranged as required. The lower portion of the vaporizing receptacle, that is vapor passage 1', is enclosed up to the condensing zone in a chamber 3 connecting with the heater chamber 2, such arrangement constituting a thermal jacket maintaining the vapors substantially uncooled until they reach the condensing zone.

In operation the vapors distilled pass up through the thermally protected, jacketed zone and substantially uncooled are introduced into the zone where provision is made for reducing their temperature and drawing off the condensate formed. Where steam has been used this will preferably be differentially condensed. In the arrangement shown in Fig. 1, by suitably grading the temperatures at the cooling coil 9, and in the auxiliary condenser 13, the oil or the like is caught by the main condenser and the steam by auxiliary condenser 13. Reduced pressure or vacuum may be used either with the steam or separately.

In the modification shown in Fig. 2 the vaporizing receptacle is a cylindrical shell 27 horizontally mounted over a heater 28 and having chambers 29 in communication with the heater chamber and extending up over the sides to form thermal jackets to the condenser zone containing a cooling coil 30 and a collecting pan 32 for directing the condensate to a suitable receiver.

In the form illustrated in Fig. 3 the vaporizing receptacle is a cylindrical shell 18 horizontally mounted over a heater and the vapor connection 20 leading to the condenser 21 is enclosed in a chamber 22 which is in communication with the heater chamber and arranged as a thermal protective or equilibrium jacket.

The construction illustrated in Fig. 4, shows another embodiment of the invention, in which the vapor connection 40 is enclosed in a jacket 43 having inlet and outlet connections 44 and 45 for a liquid of suitable temperature, and the vaporizing receptacle may be heated by the internal coil 46 or by the furnace as desired.

In these constructions condensation is guarded against from the liquid surface up to a predetermined point where it can be effected without detrimental refluxing.

While in describing my invention I have referred to certain specific details it will be understood that these are illustrative and not limitative, and the invention is to be regarded as limited only in the following claim, in which it is my intention to claim all inherent novelty as broadly as the prior art permits.

What I claim is:

10. Apparatus for the vacuum distillation of hydro-carbon oils, comprising a still including in a lower portion a heated receptacle for the liquid oil, in an upper portion a cooling zone, and a vapor passage connecting said receptacle and cooling zone; said vapor

passage being substantially unobstructed and having a cross-sectional area adequate to permit free flow of vapors, a jacket arranged about said passage, means for passing a heated fluid through said jacket to 20 maintain the temperature of the vapors, means for supplying a cooling fluid to said cooling zone, means for preventing reflux to the heated receptacle of any substantial amount of condensate formed in said cooling zone, a draw-off conduit for vapors passing the cooling zone, and means for exerting suction upon said conduit. 25
